UNITED STATES PATENT OFFICE.

HERBERT V. KENT, OF LONDON, ENGLAND.

CONSTRUCTION OF HOLLOW WALLS FOR BUILDINGS.

1,427,534.

Specification of Letters Patent. Patented Aug. 29, 1922.

Application filed July 8, 1919. Serial No. 309,415.

(GRANTED UNDER THE PROVISIONS OF THE ACT OF MARCH 3, 1921, 41 STAT. L., 1313.)

To all whom it may concern:

Be it known that I, HERBERT VAUGHAN KENT, a subject of the King of Great Britain and Ireland, residing in 76 Eaton Terrace, London, England, have invented certain new and useful Improvements in the Construction of Hollow Walls for Buildings, of which the following is a specification.

10 This invention relates to walls for buildings, and it has for its object certain improvements designed primarily to permit of the rapid construction thereof with a minimum of skilled labour.

15 Walls constructed in accordance with the present invention moreover present the advantage that a substantially continuous hollow space is formed inside the walls of the building which space can be advantageously employed to contain pipes for heating, wires for electric lighting, gas, or other pipes which, whilst being out of sight, are readily accessible.

A building embodying the present improvement moreover presents the advantages that it may be readily taken down and re-erected if desired.

In carrying the invention into effect, a number of concrete or other uprights are erected upon suitable foundations, such uprights being preferably provided with rods or other reinforcements. The uprights can be either cast or moulded separately, or they can be cast or moulded in the known manner "in situ." The uprights are provided upon the front with longitudinally disposed projections against which, as will be hereafter more fully described, slabs or panels of concrete are pressed, and these uprights also support other panels or slabs forming the interior surface, which slabs or panels are preferably formed of a non-conducting form of concrete or composition, either breeze, sawdust, or other material that will not sweat. The inner slabs are spaced a suitable distance from the outer by means of distance pieces, both the inner and outer slabs or panels being secured by clamping means applied from the inside of the building and carried by the uprights before referred to.

By this means not only may the slabs be readily and quickly placed in position but they can readily be removed when desired, the operations, except the placing of the uprights in position being readily performed by unskilled labour.

In order that the invention may be the better understood drawings are appended in which:—

Fig. 1 is an inside elevation of a wall constructed in accordance with the invention showing various stages of construction.

Fig. 2 is a longitudinal horizontal section on the line 2—2, Fig. 1.

Fig. 3 is a vertical section on the line 3—3, Fig. 1.

Fig. 4 is a view showing on an enlarged scale the means employed for clamping the outer slabs or panels in position upon the uprights.

Fig. 5 is a sectional plan showing a modification.

Referring to the accompanying drawings *a* indicates uprights formed of concrete. The uprights *a* are provided with longitudinal projections *a*¹ forming as it were a capping against which the outer edges of the outer slabs or panels *b* are pressed. *x* indicates projections formed upon or attached to the inner faces of the uprights *a* and which projections form distance pieces whereby the inner slabs are spaced at the desired distance from the outer slabs. Cast in the uprights *a* and projecting inwardly through the distance pieces *x* are bolts *c*¹ disposed at distances apart equal to the height of the slabs. *d* indicates clamps in the form of substantially U shaped metal bodies having projecting longitudinal members or feet *d*¹ at the ends. The clamps straddle the distance pieces and are of greater width than said distance pieces as shown more clearly in Fig. 4, the feet *d*¹ of said clamps bearing against the inner faces of the outer slabs *b*, the inner slabs being cut away as shown at *y*. It is possible when so desired to readily remove any one of them by means of a wedge which may be jammed on the clamps and engage the under surface of the cut away portion of the slab above. The clamp is per-

forated for the passage of the bolt c^1 and as soon as one slab has been placed in position on another on each side one of said clamps is slipped on to the bolt, a nut d^2 upon the bolt 5 causes it to press the outer slabs against the projections a^1 securing said slabs in position, the operations being continued until the desired height of wall is reached. The inner slabs or panels indicated by e bear against 10 the distance pieces x , being cut away to clear the clamps as shown at y . The inner slabs are preferably provided with plane horizontal meeting surfaces. The inner slabs are secured in position by means of a capping indicated by g , which capping may be 15 formed of wood, metal, or any other suitable material, and is perforated at suitable intervals to permit the passage of the ends of the aforesaid bolts c^1 , nuts f^1 being applied to 20 the bolts to cause the capping to press upon the slabs which are thus clamped between the inner surface of said capping and the distance pieces as shown.

Obviously the form of the clamp may be 25 varied as desired, and instead of being formed of metal it may comprise a suitably shaped block of cement or the like, or even wood may be employed for this purpose. The distance pieces may be separate from 30 the uprights as shown at the corner in Fig. 2. In the drawings in Fig. 1 on the right hand side of said figure, the capping and clamps and the inner panels are omitted. In the center the capping is omitted and the 35 clamps shown in position ready for the application of the said capping. In the left hand side of said Figure 1 the inner slabs or panels are shown in position with the capping member also in position; the extreme left end of the figure being a sectional view of the complete wall construction.

As applied to a corner the arrangement could be substantially that illustrated to the left of Figs. 1 and 2 the distance pieces in 45 this case being of angular form and comprising solid blocks of material, no separate clamps being needed here. The capping g would also be of angular cross sectional outline as shown.

50 Instead of having distance pieces the clamps themselves could act as such in which the arrangement could be as illustrated in Fig. 5 from which it will be seen that the inner panels are pressed against 55 the transverse member of the said clamp.

Claims:

1. A wall for buildings comprising slabs forming the outside of the wall, other slabs forming the inside of the wall, uprights for 60 supporting the slabs, projections upon said uprights engaging the ends of the outer slabs, bolts projecting from said uprights, clamps secured by nuts upon the bolts for securing the outer slabs to the uprights, spacing means for maintaining the inner 65

slabs in spaced relationship to the outer slabs, and means upon the aforesaid bolts for holding the inner slabs against the spacing means.

2. A wall for buildings comprising slabs forming the outside of said wall, other slabs forming the inside of said wall, uprights for supporting the slabs, projections on said uprights engaging the ends of the outer slabs, bolts projecting from said uprights, clamps 75 secured by nuts upon the bolts for securing the outer slabs to the uprights, projections upon the uprights for maintaining the inner slabs in spaced relationship to the outer slabs, and means whereby the inner slabs are 80 clamped against said projections.

3. A wall for buildings comprising slabs forming the outside of said wall, other slabs forming the inside of said wall, uprights for supporting the slabs, distance pieces for retaining the ends of the outer slabs, bolts projecting from said uprights, clamps secured by nuts upon the bolts for securing the outer slabs to the uprights, distance pieces for retaining the inner slabs in spaced 85 relationship to the outer slabs, and means whereby the inner slabs are clamped against said distance pieces.

4. A wall for buildings comprising slabs forming the outside of the wall, other slabs forming the inside of the wall, uprights for supporting the slabs, projections upon said uprights engaging the ends of the outer slabs, bolts projecting from said uprights, clamps secured by nuts upon the bolts for 95 securing the outer slabs to the uprights, spacing means for maintaining the inner slabs in spaced relationship to the outer slabs, and means upon the aforesaid bolts for holding the inner slabs against said 100 spacing means, said means comprising strips through which said bolts pass and which strips are held in position by said nuts.

5. A wall for buildings comprising slabs forming the outside of said wall, other slabs forming the inside of said wall, uprights for supporting the slabs, projections on said uprights engaging the ends of the outer slabs, bolts projecting from said uprights, clamps secured by nuts upon the bolts for 115 securing the outer slabs to the uprights, projections upon the uprights for maintaining the inner slabs in spaced relationship to the outer slabs, and means whereby the inner slabs are clamped against said projections, 120 said means comprising strips through which said bolts pass and which strips are held in position by nuts.

6. A wall for buildings comprising slabs forming the outside of said wall, other slabs forming the inside of said wall, uprights for supporting the slabs, distance pieces for retaining the ends of the outer slabs, bolts projecting from said uprights, clamps secured by nuts upon the bolts for securing 125 130

the outer slabs to the uprights, distance pieces for retaining the inner slabs in spaced relationship to the outer slabs, and means whereby the inner slabs are clamped against said distance pieces, said means comprising strips through which said bolts pass and which strips are held in position by nuts.

In testimony thereof I affix my signature in the presence of the two undersigned witnesses.

H. V. KENT.
